PHOTOELECTRIC MUSICAL INSTRUMENT

Francis J. Darke, Jr., Moorestown, N. J., assignor
to Radio Corporation of America

Application March 29, 1941, Serial No. 385,832

8 Claims. (Cl. 84—1.18)

This invention relates to an improvement in photoelectric musical instruments and, more particularly, to an improvement in the type of photoelectric organs shown, for example, in Toulon Patent 1,948,996.

In this type of instrument, the images of one or more slits are caused to traverse at a predetermined rate a diaphragm carrying the image of the sound wave to be reproduced. As the line of light traverses the image of the sound wave, a greater or less quantity thereof is permitted to pass, and the light is then directed onto a photoelectric cell producing a current which accurately varies in accordance with the sound wave image.

In such devices as heretofore constructed, the control of the timbre of the note was either impossible or inadequate. In the apparatus constructed in accordance with the present invention, the timbre may be controlled in almost endless variety and to any degree desired. This is accomplished by mounting the shutters carrying the wave shape reproductions so that they may be tilted to intercept the light beam to any desired degree.

One object of the invention is to provide an improved electric organ.

Another object of the invention is to provide an electric musical instrument in which any desired tone quality may be secured.

Another object of the invention is to provide an electric musical instrument in which the several partials involved in the reproduction of a note may be chosen at will.

Other and incidental objects of the invention will be apparent to those skilled in the art from the following specification and the accompanying drawing in which:

Figure 1 is a schematic perspective view of the apparatus,

Figure 2 is an elevation of the bank of overtone selectors indicated at 10 in Figure 1, and

Figure 3 is an end view of the overtone selectors of Figure 2 indicating their manner of operation.

Referring to Figure 1, light from a source 9 is directed by the condenser lens 11 through disc 12. This disc 12 is provided with a number of series of radial slots corresponding in relative number with the notes in an octave or greater portion of the range of the apparatus. Duplicate apparatuses may be provided for a range of any number of octaves or frequency changing devices may be used to produce the other frequencies.

Light passing through the slits in the disc 12 is selected according to the desired notes by the shutters in the shutter bank 13 which are controlled by the keys 14 in any conventional manner such as shown in U. S. Patent No. 1,848,222 of

March 8, 1932. Light passing through the slits in the disc 12 is focused by the lens 15 upon the wave images in the box 16. The lens 15 is preferably cylindrical so that each slit in the disc 12 for which the shutter is opened produces a linear image the entire height of all the wave images of the box 16 and the spacing of the slits in the disc 12 and the shutter lengths are so arranged that, as one slit image leaves the wave shape images, the next slit image of the same frequency is just entering the wave shape images from the opposite side. Light passing through the wave shape images is directed by the lenses 17 and 18 onto the photocell 19. The output of the photocell is amplified in the usual manner by an electronic amplifier and reproduced through a conventional loudspeaker or bank of loudspeakers.

The wave shape images shown in Figure 2 consist of a series of shutters 20, 21, 22, 23, 24 and 25, which vary either in outline or in transparency in accordance with the contours indicated. The shutter 20, for example, would determine the fundamental of the note to be reproduced. The shutter 21 would determine the first overtone an octave higher. The shutter 22 would determine the second overtone an octave and a fifth higher. The shutter 23 determines the second overtone which is indicated as two octaves higher. The shutter 24 would determine the fourth overtone which would be two octaves and a third higher while the shutter 25 would determine the sixth overtone two octaves and a fifth higher. It will be apparent that the overtones determined by these shutters need not be in the arrangement indicated but that some of these overtones may be omitted or others substituted or practically any desired arrangement or number of overtones may be used. Further, the tones of the keyboard may be determined by one of the higher frequencies of the shutter bank, as, for example, by the shutter 22, while the shutters 20 and 21 might be controlled by a bass coupler.

The several shutters are mounted as shown in Figure 3 so that they may be tilted at any desired angle. If one of these shutters is tilted so that its plane is parallel to the direction of travel of the light beam, it will have no effect on the light beam, and that particular tone will be eliminated. The quantity of any particular overtone which will be introduced into the note will be dependent upon the degree to which the shutter representing that particular tone intercepts the light beam, and the percentage change produced in the light beam by that particular tone in relation to the percentage change produced in the light beam by the other tones will determine the tone quality of the result.

It will be apparent that the wave shape shutters need not follow a sine wave, as shown in the

drawing, but that these shutters may have any other desired contour. For example, one of these shutters may have substantially a sine wave configuration to represent the fundamental tone and others may represent tones of entirely different quality as, for example, those produced by photographic recordings of various instruments whose tone qualities it may be desired to introduce as disclosed in U. S. Patent No. 1,998,461 of April 23, 1935.

Although the shutters 20 . . . 25 are shown as individually actuated by pull rods 30 connected to individual stops 31, it will be apparent to those skilled in the art that these pull rods may be mechanically interconnected in any desired manner so that the operation of one stop will simultaneously operate two or more of the shutters either to the same extent or in predetermined relation to each other.

I claim as my invention:

1. Tone control mechanism for an electric musical instrument of the type wherein a moving beam of light scans a stationary wave image and is thereafter directed to a photoelectric cell including a plurality of wave image shutters to produce different tones, and means for selectively adjusting each of said shutters to intercept a greater or smaller proportion of the light beam to vary the amplitude of each respective tone, the greater the amount of light transmitted to said cell, the smaller the degree of modulation of said light beam and the amplitude of the respective tone.

2. Tone control mechanism for an electric musical instrument of the type wherein a moving beam of light scans a stationary wave image and is thereafter directed to a photoelectric cell including a plurality of variable area wave image shutters to produce different tones, and means for selectively adjusting each of said shutters about the base line of the image to intercept a greater or smaller proportion of the light beam to vary the amplitude of each respective tone, the greater the amount of light transmitted to said cell, the smaller the degree of modulation of said light beam and the amplitude of each respective tone.

3. Tone control mechanism for an electric musical instrument of the type wherein a moving beam of light scans a stationary wave image and is thereafter directed to a photoelectric cell including a plurality of wave image shutters to produce different tones, each shutter being adjustable about an axis parallel with the base line of the wave images to vary the amplitude of said tones, and means for selectively adjusting said shutters to each intercept a greater or smaller proportion of the light beam to vary the amplitude of each respective tone, the greater the amount of light transmitted to said cell, the smaller the degree of modulation of said light beam and the smaller the amplitude of each respective tone.

4. Tone control mechanism for an electric musical instrument of the type wherein a beam of light scans a stationary wave image and is thereafter directed to a photoelectric cell including a plurality of variable area wave image shutters to produce different tones, each shutter being adjustable about an axis parallel with the base line of the wave image to vary the amplitude of the respective tones produced thereby, and means for

selectively adjusting said shutters to each intercept a greater or smaller proportion of the light beam, the greater the amount of said light beam transmitted to said cell, the smaller the degree of modulation of the light beam and the smaller the respective tone amplitude.

5. An electric musical instrument including a light source, scanning means defining light slits corresponding to notes, shutters defining areas corresponding to wave shapes, means for directing light from said scanning means to said shutters, means for directing light passing said shutters to a photoelectric means to produce tones corresponding with the wave image of each shutter, and means for selectively adjusting the proportion of the light beam intercepted by each of said shutters, the greater the amount of light transmitted to said photoelectric means, the smaller the degree of modulation of said light by said shutters and the smaller the respective tone amplitudes.

6. An electric musical instrument including a light source, scanning means defining light slits corresponding to notes, shutters defining areas corresponding to variable area wave shapes, means for directing light from said scanning means to said shutters, means for directing light passing the said shutters to a photoelectric means to produce tones corresponding with the wave shapes of said shutters, and means for selectively adjusting the proportion of the light beam intercepted by each of said shutters, the greater the amount of light transmitted to said photoelectric means the smaller the degree of modulation of said light by said shutters and the smaller the respective tone amplitude.

7. An electric musical instrument including a light source, scanning means defining light slits corresponding to notes, shutters defining areas corresponding to wave shapes, means for directing light from said scanning means to said shutters, means for directing light passing said shutters to a photoelectric means to create different tones, and means for selectively adjusting each of said shutters about an axis parallel to its own plane and perpendicular to the plane defined by the scanning beam for determining the proportion of the light beam intercepted by each of said shutters, the greater the amount of light transmitted to said photoelectric means, the smaller the degree of modulation of said light by said shutters and the smaller the respective tone amplitudes.

8. An electric musical instrument including a light source, scanning means defining light slits corresponding to notes, variable shutters defining areas corresponding to wave shapes, means for directing light from said scanning means to said shutters, means for directing light passing said shutters to a photoelectric means to create different tones, and means for selectively adjusting each of said shutters about an axis parallel to its own plane and perpendicular to the plane defined by the scanning beam for determining the proportion of the light beam intercepted by each of said shutters, the greater the amount of light transmitted to said photoelectric means, the smaller the degree of modulation of said light by said shutters and the smaller the respective tone amplitudes.
